CIRCUIT CONTROLLING THERMOSTAT AND
MOUNT THEREFOR

Harry Campbell Grant, Jr., New York, N. Y., assignor to Walter Kidde & Company, Inc., New York, N. Y., a corporation of New York

Application January 12, 1933, Serial No. 651,313

1 Claim. (Cl. 200—142)

This invention relates generally to circuit controlling thermostats of the type which is commonly used to control the opening and closing of electrical circuits such as are employed, for example, in electrically operated fire detecting, fire preventing and fire extinguishing systems.

More specifically the present invention relates to normally open-circuited thermostats of the type which are connected to bridge parallel circuit wires, whereby operation of any one of the parallel thermostats closes the circuit through the parallel wires and thereby effects a suitable signal or other operation.

Prior to this invention such thermostats have been constructed to be bridged across continuous parallel wires of an electrical circuit.

Prior constructions have had a most serious drawback in that the removal of a thermostat from its position in parallel with the continuous circuit wires (with the undesirable removal of its function) has no positive effect on the electrical circuit, so that no signal of any kind is rendered at a central station to indicate such removal. It will of course be apparent that such removal might be either out of pure mischief or out of criminal design to prevent the turning in of a fire signal, or it might be an entirely proper removal of a used or short-circuited thermostat with an unfulfilled or forgotten intention to substitute a new thermostat, or it might be a constructive removal as by the breaking of a wire from the thermostat to one of the parallel circuit wires.

The present invention solves this difficulty by providing a thermostat constructed so that the parallel circuit wires must be run in sections between parallel thermostats and so that the sections of the circuit wires are bridged by the thermostat when it is in its proper position. With this construction removal of a thermostat from its proper position, for any reason whatever, breaks the electrical circuit and enables a suitable open-circuit signal to be rendered at a central station.

The present invention contemplates the provision of a mounting base for the thermostat constructed so that the circuit wires are connectible in sections to the mounting box and so that the gaps in the circuit wires are bridged by the thermostat when mounted on its mounting base, the mounting base being preferably constructed so that the circuit wires must be run in sections between mounting bases and so that it is relatively more difficult to bridge the gaps in the circuit wires resulting from the removal of a

thermostat by other means than it is by the substitution of a new thermostat.

It is accordingly an object of the present invention to provide a thermostat for connection in an electrical circuit having parallel circuit wires so constructed and arranged that the circuit wires must be run in sections between parallel thermostats and so that the sections of the circuit wires are bridged by the thermostat when it is in its proper position in the electrical circuit. 5

It is another object of the present invention to provide a thermostat for connection in an electrical circuit having parallel circuit wires, so constructed and arranged that removal of the thermostat from the electrical circuit will break 10 the circuit and enable a suitable open-circuit signal to be rendered at a central station. 15

A still further object of the invention is to provide a thermostat and mounting base therefor for connection in an electrical circuit, constructed 20 and arranged so that a circuit wire is connectible in sections to the mounting base and so that the gap in the circuit wire is bridged by the thermostat when mounted on the base.

Still another object of the invention is to provide a thermostat and mounting base therefor for connection in an electrical circuit, constructed and arranged so that a circuit wire must be connected in sections to the mounting base, and so that it is relatively more difficult to bridge a 30 gap in the circuit wire resulting from removal of the thermostat by other means than it is by the substitution of a new thermostat. 25

Still another object of the invention is to provide a mounting base capable of use with a 35 thermostat in accordance with this invention.

These and other objects of the invention, not specifically enumerated above, will be apparent as the invention is described in greater detail in connection with the accompanying drawings, 40 wherein:

Figure 1 is a view, mostly all in section, of a thermostat and its mounting base shown in a position against the ceiling of a structure, the section being taken on line 1—1 of Figure 3 and 45 looking in the direction of the arrows.

Figure 2 is a plan view of the thermostat assembly of Figure 1, looking at the face thereof which is mounted next to the mounting base. 50

Figure 3 is a plan view of the mounting base of Figure 1, with the thermostat assembly removed, looking at the face thereof which receives the thermostat assembly.

Figure 4 is a view in section of the mounting 55

base, taken on line 4—4 of Figure 3 and looking in the direction of the arrows.

Figure 5 is a view in section of the thermostat assembly, taken on line 5—5 of Figure 2, the thermostat element itself being shown only partly in section.

Figure 6 is a view in elevation of a suitable thermostat element for the thermostat assembly.

Figure 7 is a plan view of a bridging piece adapted to be connected to a terminal of the thermostat.

Figure 8 is a view in elevation of one of the connector pieces inserted in the mounting base.

Figure 9 is a perspective view of the thermostat element of Figure 6 shaped as it appears in the assembled device.

Figure 10 is a view in section, on an enlarged scale, through the thermostat element of Figure 6.

20 In Figure 1 of the drawings 1 represents a mounting base, or more specifically a mounting box, of electrically insulating material, to which is secured a thermostat assembly 2, the mounting box being itself secured to any suitable structure 3. The mounting box is suitably chambered, as at 4, and is provided with secondary electrically conductive terminals 5, to which the thermostat assembly is secured by means of screws 6.

Referring now to Figures 3 and 4 which show the details of construction of the mounting box 1, the reference numeral 4 represents a chamber into which the sections of the circuit wires are inserted for connection with the electrically conductive primary terminals 7, which are electrically connected to the secondary terminals 5 in a manner to be described. Figure 3 shows two sections 8 and 9 of one of the circuit wires to which the mounting box is adapted for connection. Each of the four primary terminals 7 consists of a screw threaded insert, as shown in Figure 4, while each of the four secondary terminals 5 also consists of a screw threaded insert, as shown in Figure 1. The primary terminals and the secondary terminals are electrically connected in pairs, by electrically conductive connecting pieces 10 and 11, each pair so connected consisting of one primary terminal and one secondary terminal.

50 The mounting box is preferably made of a suitable molded electrically insulating composition, and each pair of terminals is preferably made as a unit to be inserted in the mold at the time of molding the mounting box. Such a unit, comprising one primary terminal 7, one secondary terminal 5, and a connecting piece 10 (or 11 for the longer connecting piece), is shown in Figure 8.

As shown in Figure 4, the secondary terminals 5 lie relatively close to the open face 12 of the mounting box, while the primary terminals 7 are each recessed within a surface 13.

As shown in Figure 3 each recess in a surface 13 comprises a circular portion 14 and a tangential portion 15 extending to the edge of the surface 13, the purpose of this construction being to permit an uncovered portion of a circuit wire to be inserted in the wire directing channel 15 and coiled in the circular recess 14, so that it can then be secured in position by a washer-head screw, one of which is shown at 16, electrical connection being thereby established from a section of a circuit wire, through a washer-head screw 16, a primary terminal 7, a connecting piece 10 or 11, to a secondary terminal 5.

75 While Figure 3 shows only two sections of one

circuit wire connected to two of the primary terminals, it will be seen that the opening 17 through the wall of the mounting box provides for the entry of two sections of another circuit wire, which sections can be connected to the remaining primary terminals in the same manner. When all of the circuit wire sections are connected, it will be apparent that each secondary terminal 5 is electrically connected to a section of circuit wire, and it will be further apparent that electrically bridging each of the associated pairs of secondary terminals 5 will effect closing of the gaps existing between the two sections of each circuit wire.

The manner in which bridging of a pair of secondary terminals of the mounting box is accomplished will now be described with particular reference to Figures 2 and 5, in which 18 is a base of electrically insulating material suitably chambered for the reception of the thermostat element 19. Figure 6 gives a somewhat better view of the thermostat element, the details of construction of which form no part of the present invention; while Figure 9 shows the shape which the thermostat element assumes in the assembled device. For the purpose of the present description it is sufficient to note that the thermostat element is provided with two electrically separated terminals 20, suitably perforated at 21, the thermostat element being designed to close a circuit between the terminals 20. In other respects the construction of the thermostat element may be as desired. Thus, for example, the construction may be the same as that shown in Letters Patent of the United States No. 1,274,248. Such a thermostat element is shown, by way of example, in section in Figure 10. For the purpose of bridging the thermostat terminals 20 across the secondary terminals 5 of the mounting box 1, bridging pieces 22, shown in Figure 7, are employed; each bridging piece being provided with suitable perforations 23 and 28, the purpose of which will be described.

The base 18 (Figure 5) is provided with screw-threaded recesses 24, with a shallow recess 18' conforming to the outline of the thermostat element 19, and with slots 25, so that the thermostat element 19 can be assembled into the recess 18' in the base 18 with its terminals 20 passed through the slots 25 and bent over to lie in close contact with the opposite upper surface of the base 18, the perforations 21 in the terminals 20 being arranged to coincide with the screw-threaded recesses 24 in the base 18. As will be seen in Figure 2, recesses 26 are provided in the upper surface of the base 18 conforming to the outline of the bridging pieces 22 and deep enough to receive said bridging pieces. When the thermostat element 19 has been assembled into the base 18 as already described, a bridging piece 22 is placed in each recess 26 over a terminal 20 and in direct contact therewith. The perforations 23 of the bridging pieces are arranged to coincide with the perforations 21 of the thermostat terminals 20, so that both the thermostat and the bridging pieces may be held in position by the screws 27. It should be noted that each bridging piece is provided with perforations 28 which are so arranged that they coincide with suitable passages 28' in the base 18 and with the screw-threaded recesses in the secondary terminals 5 of the mounting box 1.

The manner in which the thermostat assembly is connected to the mounting box 1 will best be understood with reference to Figures 2 and 3, the 75

thermostat assembly as shown in Figure 2 being first rotated through an angle of 90° and then turned over so that the bridging pieces 22 face downwardly with respect to the surface of the drawings. The thermostat assembly is then applied to the open face of the mounting box 1 as illustrated in Figure 1, being received within the recess shown more clearly in Figure 4, at which time, by reason of the specific construction already described, the perforations 28 in the bridging pieces 22 of the thermostat assembly and the corresponding perforations 28' in the base 18 will overlie and coincide with the screw-threaded recesses in the secondary terminals 5 of the mounting box 1.

15 The screws 6, shown in Figure 1, are then passed through the holes 28 in the bridging pieces and the holes 28' in the base 18 and are threaded into the screw-threaded recesses in the secondary terminals 5 of the mounting box 1 so as to hold the thermostat assembly securely to the mounting box. Electrical contact will then be established between the bridging pieces 22 and the secondary terminals 5 by reason of the surface 20 contact maintained therebetween by the screws 6; and not only will each of the bridging pieces 22 be bridged across a pair of secondary terminals 5, thus connecting the isolated sections of the parallel circuit wires already referred to, but the 25 thermostat element 19 of the thermostat assembly will be bridged across the parallel circuit wires.

Referring to Figure 10, which shows the details of construction of one form of thermostat element which may be employed, by way of example, in conjunction with the present invention, the thermostatic circuit closing element proper is enclosed in a casing which is formed directly of the two circuit terminals, these terminals being formed as two discs 30 and 31 having integral upturned tabs 20 for connection to the base 18 of the thermostat assembly, the disc 31 being somewhat smaller in diameter than the disc 30 so that when laid upon the disc 30, its 40 peripheral edge will be spaced from a flange 32 upon the disc 30.

Each of the terminal discs 30 and 31 preferably has annular corrugations pressed therein to increase the heat absorbing surface, and the discs 50 also have nesting central depressions 33 and 34, the depression 33 being adapted to receive a disc 35 of easily fusible material, which constitutes the thermostatic circuit closing element proper. The opposed faces of the terminal discs 30 and 55 31 are insulated from each other, preferably by a thin disc 36 of varnished silk or other suitable insulating material perforated at 37 over the fusible disc 35, the disc 36 thus insulating the fusible disc also from the disc 31 but permitting 60 the fusible material of the disc 35 to spread through the perforations 37 upon fusing, to bridge the terminals 30 and 31. The insulating disc 36 is preferably of such diameter that it fits closely within the space bounded by the flange 32 of the disc 30.

65 Each of the discs 30 and 31 has a plane marginal portion outside the corrugations, the purpose of this marginal portion being to provide a flat clamping surface upon each disc, adapted to cooperate with the corresponding surface upon the other disc to insure a tight joint about the edges when the discs are clamped together to form a closed casing. In order to maintain the insulating disc substantially in one plane and to 70 prevent injury to this disc by excessive pressure 75

against the corrugations when the parts are clamped into final relation, an annular insulating piece 38 is preferably located upon the plane marginal portion of the disc 30 in such position that it supports the margin of the disc 36, this 5 annular piece 38 being preferably of such thickness that the disc 36 will rest against the upper edges of the corrugations in the disc 30. The corrugations of the two discs 30 and 31 preferably register so that a slight corrugating of the 10 material of the disc 36 will usually be effected by the clamping pressure exerted in clamping the parts into their final relation.

The opposed faces of the discs 30 and 31 are insulated from each other by the insulating disc 15 36. The edge of the disc 31 is preferably insulated from the flange 32 of the disc 30 by an air gap, and in order therefore to insure maintenance of the edge of the disc 31 in spaced relation to the flange 32 of the disc 30, an annular insulating 20 piece 39 is provided which has an outer diameter corresponding to the diameter of the space within the flange 32 and an inner diameter corresponding to the diameter of the outer corrugation of the series of corrugations on the disc 31. 25 Thus, when the parts are assembled, the ring 39 will center the disc 31 in spaced relation to the flange 32 of the disc 30. The ring 39 also insulates the overturned flange 32 of the disc 30 from the disc 31. In order to insure the insulation of 30 the tab 20 of the disc 31 from the disc 30 when the parts are clamped together, the flange 32 is interrupted at a point opposite said tab 20, proper spacing of the elements being provided. Of course, the flange 32 is also interrupted at the 35 point where the tab 20 of the disc 30 projects, so that proper clamping may be effected.

In order to insure quick and positive operation of the device, it is important that the parts of the terminals to be bridged shall be as close together 40 as possible, and, moreover, that they preferably exert a pressure upon the fusible disc 35 to cause it to flow through the perforations 37 of the insulating disc 36 as soon as it begins to fuse. To this end the terminal discs 30 and 31 are preferably so tensioned, either before or during the clamping operation by which they are joined to form a casing, that the nesting central depressions 33 and 34 of the two discs tend to clamp between them the fusible disc 35 and the opposed 50 portion of the insulating disc 36, having therein the perforations 37.

The above completes the description of the thermostat element so far as it concerns the present invention, it being kept in mind that the details of construction of this element form no part of this invention. A more complete description of this element, which is here illustrated by way of example only, will be found in the hereinabove referred to Letters Patent of the United States 60 No. 1,274,248.

With further reference to Figure 4, it should be noted that the holes 29 are provided for screws or bolts to hold the mounting box in any desired position.

It should also be noted that with the construction of the mounting box as described, once the mounting box is connected to the circuit wires, it is relatively more difficult to bridge the gaps in the circuit wires left by the removal of a thermostat by any other means than by the simple substitution of a new thermostat for a used one, the invention thus facilitating proper servicing of the apparatus.

From the foregoing description it will be seen 75

that my invention embodies the important objects pointed out at the beginning, providing, as it does, a thermostat and mounting base therefor, in which circuit wires must be run in sections to and between mounting bases; in which mounting of a thermostat on its base completes a circuit through the sections of wire; in which, conversely, removal of a thermostat from its mounting base breaks a circuit through said sections and enables a suitable signal to be rendered at a control station; in which, in fact, even loosening of a thermostat sufficiently to break the circuit, as by the loosening of a single holding screw, at one point, is sufficient to turn in a trouble signal at the central station; and in which, finally, the thermostat can be removed and replaced without disturbing any circuit wires.

However, while the invention has been described in connection with the details of construction shown in the accompanying drawings, it will be apparent to those skilled in the art that the invention can be embodied in other forms of

construction without departure from the spirit and scope of the invention, and for this reason I do not wish to be strictly limited to the disclosure but rather to the scope of the appended claim.

A thermostat and mounting base assembly for connection in an electrical circuit comprising a mounting base provided with two pairs of spaced terminals having screw threaded recesses therein, a thermostat provided with a pair of terminals, each having a pair of spaced apertures adapted to coincide with the screw threaded recesses of a pair of mounting base terminals when the thermostat is positioned on the mounting base, and a plurality of screw threaded members adapted to pass through said apertures and engage in said screw threaded recesses and serving to mount the thermostat on the mounting base and to effect electrical connection between the corresponding thermostat and mounting base terminals.
